UNITED STATES PATENT OFFICE

EDWARD E. SIMPSON, OF TULSA, OKLAHOMA

PLUG PACKER

Application filed January 4, 1928. Serial No. 244,514.

This invention relates to plug packers for use in oil and other wells, and is more particularly concerned with a plug packer for oil wells embodying novel constructions and combinations of parts and adapted for use as a well bottom plug or as a plug to shut off gas or water.

An object of the invention is to provide a plug packer having means by which it may be determinately positioned above the bottom of the well hole. The diameter of the well hole at its bottom is usually enlarged to such an extent that a packer of a diameter insertable in the well casing cannot be expanded sufficiently to equal the enlarged diameter of the bottom and plug packers can best be operated in the casing or well bore above the bottom. My invention provides means for variably positioning the packer to shut off gas or water strata below the oil bearing strata, the desirability of which is obvious.

These and other objects and advantages will be more fully apparent from the following detailed specification when read in conjunction with the accompanying drawings forming part thereof and in which:

Figure 1 is a view in vertical section of the bore of a well having the packing unit positioned therein for the packing operation, the packer being shown in vertical section.

Figure 2 is a similar view with the packer expanded to plug off the well bore at the desired point.

Figure 3 is a horizontal sectional view through the expansible packing member taken on line 3—3 of Figure 1.

Figure 4 is a horizontal sectional view through the body of the packer at the line of the shearing pin, the section being taken on line 4—4 of Figure 1.

Figure 5 is a detail of the lower end of the expanding mandrel showing the packer retaining slip mounted thereon.

Referring to the drawings by numerals, 1 indicates the conventional casing of a well bore 2, which casing, as usual, terminates above the bottom of the well bore. The plug packer of the present invention is of a size permitting its insertion downwardly through

the well casing to the desired point and comprises a main tubular body portion including a surmounting expansible tubular packing member, an expanding mandrel above said body portion having a shank extending through its bore and coupled thereto by a shearable pin, and when necessary or desirable, a spacing member coupled to and depending from the bottom of the body portion determinately to space the packer from the bottom of the well.

The base of the packer comprises a tubular body 3 of wood, such as cypress having a metal head 4 applied to its lower end and having the face of its upper end formed with an annular channel 5, in which is seated a boss 6 formed at the lower end of a tubular expansible packing sleeve 7 which may be of rubber or rubber composition and which with the lower body 3 of the packer is of a diameter closely fitting the internal diameter of the well casing so that the most effective results from its expansion may be secured.

The bore 8 at the lower end of the expansible sleeve 7 is of less diameter and extent than the bore 9 at the upper end of the sleeve providing an annular shoulder 10 separating these two bores of different diameters. The bore 8 of the expansible sleeve and the bore of the wood base 3 of the packer are the same and are lined by a tube 11, the lower end of which projects beyond the head 4 and is externally threaded to receive the upper threaded end of a spacing tube 12 by means of which the packer is determinately positioned from the bottom of the well. The lining tube 11 extends above the shoulder 10 of the expansible sleeve and is externally threaded to receive a protecting sleeve 13 threaded thereon.

Adjacent to and below the annular seat 5, the base 3 of the packer body is traversed by a bore designed to seat a shearable pin 14. This pin extends through an alining bore formed in the elongated shank 15 at the lower end of an expanding mandrel which above the shank 15 tapers outwardly providing a plug expanding tapering portion 16 which normally in the unexpanded relation of the mandrel and packer is positioned above the

upper end of the expandable sleeve 7 as shown in Figure 1. The upper end of the tapering portion 16 is formed with a collar 17 and with a neck 18 extending thereabove and provided with an annular series of teeth 19 for engagement by a fishing tool when it is necessary forcibly to withdraw the mandrel. A bore 20 is provided in the neck to receive a suitable coupling by which the packer and mandrel may be lowered, and by which they may be connected to the drilling bit for driving the mandrel downwardly.

If it is desired to set the plug packer at the bottom of the well bore, the spacing tube 12 is uncoupled or if it is necessary to anchor the plug a determinate distance above the bottom, tubing 12 of the requisite length is coupled to the lower end of the packer lining tube 11. The packer is lowered to the desired point by means of a wire or cable whose lower end is passed through the opening 20 in the neck of the mandrel. When the plug packer reaches the bottom of the well bore, a drilling hitch is taken and driving started, whereupon the pin 14 will shear off and the mandrel will be driven down to insert its tapering portion 16 within the expandable sleeve 7 compressing it downwardly and expanding it outwardly firmly into all crevices of the well wall as suggested by Figure 2, after which the wire or cable is pulled from the neck 20 leaving the mandrel in expanding relation to the packing plug.

The weight of the mandrel alone is insufficient to retain the packer in expanded position against the pressure of gas or other fluid acting thereagainst. I have therefore provided means for locking the mandrel with the packer in expanded position. The shank portion 15 of the mandrel is recessed to provide a tapering notch 21 having thereon a vertically extending rib or tongue 22. A toothed slip 23 of corresponding taper is formed on its under face with a vertically extending groove 24 by means of which the slip is seated and retained upon the tapered face of the shank 15, resting by gravity at the lower end of the tapering recess as indicated in Figure 1. The tapered notch 21 is of greater extent than the length of the slip 23 permitting the latter to ride up therein when the shank of the mandrel is inserted in the upper end of the lining tube 11. When the mandrel is driven downwardly to expand the packer, the slip will ride upwardly on its seat permitting the mandrel to be driven down to packer expanding position. Retraction of the mandrel, however, from expanding position through the force of gas or other fluid pressure acting against the packer is prevented however, since upward movement of the mandrel shank forces the slip 23 outwardly against the lining tube 13 and causes its teeth to bite into said tube to resist and prevent such retraction of the mandrel. The

slip, however, will permit forcible retraction, when necessary, so that the mandrel with its attached packer may be withdrawn for repositioning in the event of error in its initial positioning. This forcible withdrawing may so injure the lining tube 11 or the expandable rubber sleeve so as to require replacement of one or both, but the packer is constructed to permit this to be easily effected. The protecting sleeve 13 is designed to prevent splitting of the upper end of the lining tube 13 in initially inserting the shank 15 of the mandrel with its locking slip and also to protect the upper end of the tube should the lower tapering end of the mandrel be driven partially therein in the expanding of the packing sleeve 7.

The specific form of packer as described herein, while it represents a preferable embodiment of the invention, is intended as illustrative rather than restrictive of the invention and structural modification and adaptation thereof to meet varying conditions is contemplated in consonance with the spirit of the invention and the scope of the appended claims.

What I claim therefore, and desire to secure by Letters Patent is:

1. A packer comprising a tubular rigid body portion surmounted by an expandable tubular packing member with the bores of said body portion and member in axial alignment, said packing member having a bore coincident with that of the body portion at its lower end enlarged thereabove to provide a shoulder, a tube lining the adjoining bores of said body portion and packing member with its upper end positioned above said shoulder and provided with a protecting sleeve and with its lower end projecting below the base of said body portion and formed to couple thereto a spacing member to position said body determinately above the bottom of the well bore, an expanding mandrel suspending said body portion having an elongated shank at its lower end extending in the bore of and coupled to said body portion by a pin shearable by forcible relative inter-engaging movement of mandrel and packer, the mandrel above the packer in its coupled position having an outwardly tapering portion adapted to enter and expand outwardly, said packing member upon forcible interengaging relative movement shearing said pin.

2. A packer comprising a tubular rigid body portion surmounted by an expandable tubular packing member with the bores of said body portion and member in axial alignment, said packing member having a bore coincident with that of the body portion at its lower end enlarged thereabove to provide a shoulder, a tube lining the adjoining bores of said body portion and packing member with its upper end positioned above said shoulder and provided with a protecting sleeve and

with its lower end projecting below the base of said body portion and formed to couple thereto a spacing member to position said body determinately above the bottom of the well bore, an expanding mandrel suspending said body portion having an elongated shank at its lower end extending in the bore of and coupled to said body portion by a pin shearable by forcible relative inter-engaging movement of mandrel and packer, the mandrel above the packer in its coupled position having an outwardly tapering portion adapted to enter and expand outwardly, said packing member upon forcible interengaging relative movement shearing said pin, the shank of said mandrel having a tapering notch therein slidably mounting a tapered toothed slip and effective to wedge said slip against said body lining tube upon movement of said mandrel away from packer expanding position.

Signed at Tulsa, in the county of Tulsa and State of Oklahoma, this 29th day of December, A. D. 1927.

EDWARD E. SIMPSON.
